UNITED STATES PATENT OFFICE

DWEN R. YOUNGER, OF WOODLAND, CALIFORNIA, ASSIGNOR OF ONE-HALF TO EARL L. YOUNGER, OF WOODLAND, CALIFORNIA

FUEL-FEEDING DEVICE

Application filed March 10, 1928. Serial No. 260,556.

The invention relates to a tank arranged to deliver liquid fuel by gravity to a carburetor or the like, and which is arranged to receive the fuel from a lower supply tank by 5 vacuum means.

A general object of the invention is to provide an improved tank of the class described in which the intake of fuel to the filling chamber thereof is controlled by a float.

10 A more specific object of the invention is to provide a tank of the class described in which only a single port need be float-controlled, thereby permitting the use of an extremely simple float valve structure.

15 Another object of the invention is to provide a tank of the character described in which the control means provided therein involves a minimum number of moving parts.

20 A further object of the invention is to provide a tank of the class described which is arranged to be filled by and upon the turning over of an engine with which it is associated, whereby no need for priming it ever occurs.

25 The invention possesses other objects and features of advantage, some of which, with the foregoing, will be set forth in the following description of a preferred form of the invention which is illustrated in the accompanying drawings and in which,

30 Figure 1 is a side view showing a tank incorporating the invention operatively associated with an internal combustion engine and the supply tank therefor.

35 Figure 2 is an enlarged vertical mid-sectional view through the tank.

Figures 3 and 4 are views similar to Figure 2, but with the operative parts of the device disposed as for different parts of the operative cycle thereof.

40 Figure 5 is a vertical mid-sectional view through a tank having incorporated therewith a modified form of the invention.

As illustrated, the vacuum tank 6 incorporating my invention is associated with the gasoline engine 7 of a motor vehicle, said engine including a carburetor 8 and an intake manifold 9 for conveying the carburetted fuel from the carburetor to the engine cylinders. The tank 6 is arranged to be mounted at a 50 point of the vehicle which will always be dis-

posed somewhat above the level of the carburetor, and is here shown mounted on the vehicle dash 11 whereby fuel may discharge therefrom by gravity to the carburetor 8 through a connecting conduit 12. A supply conduit 13 connects the tank 6 with a fuel supply tank 14 disposed at some distance from and below the carburetor, and the former tank is connected with the intake manifold 9 by means of a conduit 15 whereby the suction in the manifold may be communicated to the tank.

55 A partition 16 divides the tank 6 to define therein an upper chamber 17 and a lower chamber 18. The upper chamber 17 is connected with the conduit 15 at a port 19 in the top of the tank and with the supply conduit 13 at a tank port 20 slightly below the level of the port 19. Connection of the discharge conduit 12 to the tank is made at the bottom 60 of the chamber 18. It will thus be clear that the upper chamber 17 comprises an intake or vacuum chamber, while the lower chamber 18 is a discharge chamber, and reference to said chambers will hereinafter be made accordingly.

65 Extending downwardly into the chamber 18 from a perforation 21 in the partition 16 is a pipe 22, said pipe being provided at the lower end thereof with a normally closed one-way valve 23 arranged, under certain conditions to be hereinafter described, to permit a flow of fuel therethrough from the chamber 17 to the chamber 18. As here shown, the pipe 22 is generally L-shaped with the 70 outlet end thereof defining a seat inclined slightly out of the vertical and against which a valve plate 24 is arranged to be gravitationally seated.

75 Figures 3 and 4 are views similar to Figure 2, but with the operative parts of the device disposed as for different parts of the operative cycle thereof.

80 Headed pins 25 extend from the valve seat 24 through registering openings in the plate 24 whereby the latter may be retained in opposed relation to the valve seat, it being noted that though the present valve structure constitutes a flapper valve, other types of one-way valves might be used in lieu thereof.

85 Mounted in the intake chamber 17 is a member 26 providing therein a float well 27 and having upper and lower end walls 28 and 29 respectively. A float 31 is disposed in 90

the well 27, said float being provided with axially aligned rods 32 and 33 extending upwardly and downwardly therefrom and slidably engaged in openings 34 and 35 respectively provided in the end walls 28 and 29 of the member 26, whereby the float may be guided for rectilinear and vertical movement in the cavity 27. An opening 36 is provided in a side of the member 26 adjacent the top thereof whereby the well 27 is connected with the cavity of the tank chamber 17 in which it is disposed. The lower opening 35 is arranged to loosely receive the rod 33 whereby a passage for the flow of liquid along the rod is provided, the effective area of such passage being, however, considerably less than is that of the opening 36 whereby liquid may be supplied to the cavity 27 through the opening 36 at a faster rate than it may escape through the opening 35. The wall 28 is perforated for connecting the chamber portions above and below it and functions as a splashing baffle as well as to provide the guide opening 34.

25 The rod 32, it will now be noted, is axially aligned with the port 19 at the top of the tank, and said port is provided with a valve seat 37 at the inner end thereof with which a valve plug 38 provided at the upper end of the rod 32 is arranged to engage when the float is in a raised position thereof. As shown, the seat 37 is conical and the extremity of the rod 32 is conically tapered for providing the plug 38. In this way, the necessary valve structure is provided in an extremely simple manner and involves a minimum of parts.

40 The lower chamber 18 is vented from a side thereof and above the level of the flapper valve 23 by means of a pipe 39 which extends to a level somewhat above that of the top of the chamber 17. The pipe 39, it is noted, is not only arranged to insure the maintenance of atmospheric pressure in the lower or discharge chamber 18 of the tank but is also arranged to provide for the relief of the vacuum in the intake chamber 17 created by a flow of fuel therefrom through the flapper valve 23 when the suction port 19 is closed by means of the plug 38. Accordingly, and 45 as shown, a small port 41 is provided in the tank partition 16, preferably at a point thereof adjacent the inlet end of the pipe 39, such port constantly serving to permit an upward flow of fluid from the upper portion of the chamber 18. The port 41, for reasons to be hereinafter set forth, is extremely small, and is therefore preferably protected from clogging by means of an annular guard flange 42 mounted on the partition at the port 41 to 50 extend upwardly therefrom with its bore in registration with the port 41.

46 The structure now described operates in the following manner. Assuming the conditions shown in Figure 2 in which the suction port 19 is open, the suction in the manifold and

suction conduit 15 operates to create a partial vacuum in the intake chamber 17, the result of this action being that the flapper valve 23 is held shut and the liquid is drawn from the supply tank 14 through the conduit 13 and so into the chamber 17. This flow of liquid into the chamber 17 is arranged to continue until and following the recurrence of an overflow of liquid from the chamber 17 through the opening 36 at the top of the member 26 and so into the float well 27 of such member. As the level rises in the chamber 17 the liquid will tend to seep upwardly through the opening 35 and around the rod 33 therein, but as the float overlies such opening, such seepage is relatively small. After the liquid is running into the well 27, the latter is arranged to fill to such a level that the float is raised to finally dispose the valve plug 38 in the seat 37 and so seal the suction port 19.

55 While the foregoing operative steps of the device are being effected, and prior to the complete closing of the suction port, a certain amount of air is allowed to pass upwardly through the liquid in the chamber 17 from the port 41, such flow of air being so slight, however, as to not appreciably influence the effectiveness of the manifold suction pull to draw the liquid into the chamber 17 through the supply conduit 13, it being noted that this air flow decreases slightly as the liquid level in the chamber 17 rises on account of the added resistance of the liquid to such flow. When the suction port 19 is almost closed, as shown in Figure 3, the effective suction in the chamber 17 becomes so reduced that a full stream no longer flows into the chamber 17, yet the full suction of the manifold operates to urge the plug 38 to its seat, with the result that just as the suction in the chamber 17 ceases to be effective on account of the relief afforded by the air from the port 41, the float and plug complete their upward travel with an accelerated movement which is considerably faster than the previous upward movement thereof.

100 With the suction port closed whereby the liquid in the chamber 17 is no longer held against discharge into chamber 18 by reason of the manifold suction, the only force tending to prevent a discharge of such liquid through the pipe 22 and flapper valve 23 is that of the atmosphere against the latter valve, but this is balanced by the admission of air from the chamber 18 through the port 41, and the liquid therefore flows from the chamber 17 into the chamber 18 through the valve 23 at a rate determined by the size of the port 41. As the liquid level in the chamber 17 lowers, so is the liquid in the float well allowed to escape through the opening 35, the latter continuing until such a time as the float lowers sufficiently to lower the plug 38 from the seat 37 and so restore the opera-

tiveness of the intake manifold suction whereby the foregoing cycle may be repeated.

It will thus be clear that the lower chamber 18 is arranged to intermittently receive charges from the chamber 17 at a rate determined in part by the size of the opening 41 and in part by the suction of the manifold, the latter depending on the rate of operation of the engine which in turn controls the rate at which 10 the fuel is withdrawn from the chamber 18. Obviously, the relative sizes of the various ports of the device would be such as would insure a constant supply of fuel in the chamber 18, any excess merely tending to slow 15 down the discharge from the chamber 17 and so eliminating any necessity for a return or overflow pipe to the supply tank.

It will now be noted that an important feature of the present vacuum tank structure 20 lies in the fact that the parts thereof are so related that the tank, even though empty when an engine is turned over for starting, is self-filling under these conditions whereby it need never be "primed," as is necessary with most 25 vacuum tank structures now found on the market. Furthermore, the provision of the float well 27 not only assists in making possible the quick closing of the suction port referred to, but is also an important factor in 30 providing for a smooth and uniform operation of the device, particularly when it is used for controlling the fuel supply for internal combustion engines installed on vehicles.

35 Under some circumstances, the provision of a special float well may be dispensed with and the float installed directly in the intake chamber. Such a structure is shown in Figure 5 herewith in which intake and discharge 40 chambers 51 and 52 are defined on opposite sides of a partition 53. For guiding the float 54 in the axial line of the suction port seat 55, an upper partition 56 is provided, while the discharge opening 57 of the lower and main 45 partition 53 is provided with a perforated sleeve 58 extending upwardly therefrom to provide at its upper end a guideway for the lower rod 59 of the float 54.

In this manner, a simplified structure results, such structure being otherwise formed and operating as the embodiment first described.

I claim:

1. In a fuel feeding system, a tank providing a vacuum chamber having a one-way pressure controlled discharge valve therefor, means for producing a partial vacuum in said chamber for drawing liquid thereinto from an external source, means periodically operative to render said vacuum producing means inoperative with respect to said chamber, and means providing for a restricted and constant communication of said chamber with the atmosphere through the liquid in said chamber.
2. In a fuel feeding system, a tank provid-

ing a chamber having a gravity discharge passage at the bottom thereof, a one-way pressure controlled valve in said passage, a liquid supply tank, means for producing a partial vacuum in said chamber for drawing liquid thereinto from said supply tank, a second valve controlling the operativeness of said first means with respect to said chamber, a float in said chamber for controlling said second valve, and a constantly open air intake at the bottom of said chamber, said intake being of a size to permit a creation of the partial vacuum in said chamber when said second valve is open, and to admit air through the liquid in the chamber for permitting a controlled gravity flow of liquid from the chamber when said second valve is closed.

3. In a liquid lifting system, a tank providing a chamber having a gravity discharge passage at the bottom thereof, a one-way pressure controlled valve in said passage, a source of liquid, means for producing a partial vacuum in said chamber for drawing liquid thereinto from said source thereof, a second valve controlling the operativeness of said first means with respect to said chamber, means in said chamber for controlling said second valve in accordance with the quantity of liquid therein, and a constantly open air intake at the bottom of said chamber for admitting air into said chamber through the liquid therein.

4. In a liquid lifting device, a suction chamber, means to intermittently produce a suction in said chamber for lifting liquid thereinto, and means providing a constantly open air intake for the admission of air to the chamber and through the liquid therein when suction obtains in said chamber.

5. In a liquid lifting system, a vacuum chamber having a pressure-controlled port for the gravity discharge of liquid therefrom, means providing an exhaust port for the chamber, a valve operative at said port, a cup member mounted in said first chamber and providing a float well, said cup member provided with constantly open intake and discharge ports at the top and bottom thereof respectively for receiving and discharging liquid from and to said vacuum chamber, said lower port being smaller than said upper port, and a float in said float well controlling said valve.

In testimony whereof, I affix my signature.

DWEN R. YOUNGER. 120
